WELL DRILL

Jesse C. Wright, Los Angeles, Calif., assignor to
 Globe Oil Tools Company, Los Nietos, Calif.,
 a corporation of California

Application September 18, 1933, Serial No. 689,896

7 Claims. (Cl. 308—4)

This invention relates to well drilling tools, and relates more particularly to well drills for use in the rotary method of well drilling. It is a general object of the present invention to provide a practical efficient well drill having a simple effective bearing means and guiding means.

Another object of the invention is to provide a well drill that is operable to drill a straight vertical bore.

10 It is another object of the invention to provide a well drilling tool having improved bearing and guiding parts that are effective in guiding the tool to make a straight vertical bore and in stabilizing and steadyng the tool during operation.

15 It is another object of the invention to provide a well drill having bearing and guiding parts that stabilize and guide the drill to make a straight vertical bore without causing it to bind or stick in the bore.

20 It is another object of the invention to provide a well drill having guiding parts that engage the wall of the well bore at points above the cutting parts to guide the drill to make a straight bore, which guiding parts wear away as the cutting parts become reduced in active diameter or size 25 through wear so that they continue to be effective in guiding the drill throughout the life of the cutting parts without causing the drill to jam or stick in the well.

30 It is another object of the invention to provide a well drill including guiding parts that are effective in stabilizing and guiding the drill without scoring or cutting into the wall of the well bore and without interfering with the free circulation 35 of fluid or rotary mud through the well.

35 It is a further object of the invention to provide a well drill of the character mentioned having a simple and effective means for removably mounting the bearing and guiding parts on the body of 40 the tool so that they may be easily and quickly replaced.

45 Other objects and features of the invention will be best and fully understood from the following detailed description of the invention, throughout which description reference is made to the accompanying drawings, in which:

Fig. 1 is a longitudinal detailed sectional view of a well drill embodying one form of the present invention. Fig. 2 is a transverse detailed sectional view taken as indicated by line 2—2 on Fig. 1. Fig. 3 is an enlarged transverse detailed sectional view taken as indicated by line 3—3 on Fig. 1. Fig. 4 is an enlarged fragmentary exterior view of one of the enlargements for carrying 55 a bearing part with the bearing part removed.

Fig. 5 is a longitudinal detailed sectional view of a double barrel core drill embodying another form of the invention. Fig. 6 is an enlarged transverse detailed sectional view taken as indicated by line 6—6 on Fig. 5. Fig. 7 is an enlarged fragmentary exterior view of one of the enlarged parts of the body for carrying a bearing part. Fig. 8 is a longitudinal detailed sectional view of a single barreled core drill or core receiving drilling tool embodying another form of the invention. Fig. 9 is a transverse detailed sectional view taken as indicated by line 9—9 on Fig. 8, and Fig. 10 is an enlarged fragmentary view of one of the body enlargements for carrying a bearing part of the character illustrated in Figs. 8 and 9.

5 The present invention may be carried out or embodied in well drills of various types, for example, it may be embodied in rotary well bits of various forms, single barreled core drills or core receiving drilling tools, double barreled core drills, 10 etc. Throughout the following detailed description, I will disclose several typical forms and applications of the invention, it being understood that the invention is not to be considered as limited or restricted to the specific details or 15 applications about to be described, but is to be taken as including any features or modifications that may fall within the scope of the claims.

20 The form and application of the invention illustrated in Figs. 1 to 4 inclusive of the drawings, includes generally, a body 10, a pilot bit or cutter 11 on the lower end of the body, a reaming or bore enlarging cutter 12 on the body spaced above the pilot cutter 11, bearing parts or guiding parts 13, and means 14 for removably attaching the 25 parts 13 to the body 10 to project therefrom for engaging the wall of the well bore.

30 The body 10 of the drill is an elongate member adapted to be attached to the lower end of an operating string of drill pipe, or the like. In the 35 particular case illustrated in the drawings, the body 10 is integral and includes an upper portion 15 and a lower portion 16 of reduced diameter. The lower portion 16 of the body is preferably 40 comparatively long as illustrated in the drawings. A screw threaded pin 17 is provided on the lower 45 end of the reduced portion 16. A central longitudinal fluid passage A extends through the body 10 from one end to the other to carry the circulation fluid or rotary mud to the pilot cutter 11 at the lower end of the drill.

50 The pilot cutter 11 which is attached to the lower end of the reduced body section 16 is provided to make a bore B of comparatively small 55 diameter. The pilot cutter 11 includes a body or

shoe 18 and cutting parts 19. The upper portion of the shoe 18 is in the nature of a box having a threaded socket 20 for receiving the pin 17. In accordance with the broader principles of the invention, any form of cutting parts may be provided on the pilot cutter 11. In the simple form of the invention illustrated in the drawings the cutting parts 19 are in the form of blades projecting downwardly and outwardly from the shoe 18. Certain of the cutting blades 19 have upwardly and inwardly stepped lower cutting edges while others of the blades have comparatively narrow straight lower edges. Central blades 21 are provided on the lower end of the shoe 18 for removing or cutting away the core left by the blades 19. The shoe 18 of the pilot cutter has an internal chamber 22 in communication with the lower end of the fluid passage A. Ports 23 are provided in the shoe 18 to discharge fluid from the chamber 22 at or adjacent the cutting blades 19. The cutting blades 19 of the pilot cutter 11 have comparatively long outer or reaming edges 26 and are operable to cut the bore B to pass the lower portion 16 of the body with substantial clearance.

The cutter 12 is provided on the body 10 at a point spaced a considerable distance above the pilot cutter 11 to enlarge the well bore so as to freely and safely pass the upper portion of the body 10 and the drilling string. The reaming cutter 12 is carried by the large upper portion 15 of the body 10 and includes a body or shoe 24 and cutting parts 25. The shoe 24 is tubular or annular and surrounds the lower end of the body part 15. In the particular case illustrated in the drawings, the shoe 24 is screw threaded on the body part 15, it being understood that it may be attached to the body in any suitable manner. In the particular drill illustrated the cutting parts 25 of the reaming cutter are in the nature of blades and project downwardly and outwardly from the shoe 24. The blades 25 have lower cutting edges 27 which engage the formation at the upper end of the smaller bore B to form a shoulder at this point and to enlarge the bore. The outer edges or reaming edges 28 are provided on the cutting blades 25 and are comparatively long to have substantial engagement with the walls of the enlarged portion of the well bore. The outer lower corners of the cutting blades 25 may be bevelled away and sharpened in the manner clearly illustrated in Fig. 1 of the drawings.

The bearing and guiding parts 13 are provided to engage the wall of the well bore to maintain the body of the drill stabilized in the bore and thus guide the drill to make a straight vertical hole, and through their engagement with the wall of the bore, stabilize the drill during operation. In accordance with the broader aspects of the invention, the bearing parts or guiding parts 13 may be located on any suitable portion of the drill body 10. Where the drill has a pilot cutter 11 spaced from and operating in advance of a reaming cutter 12, the guiding parts 13 are very effective when mounted on the body 10 at points between the the two cutters. It is a feature of the invention that the bearing parts and guiding parts 13 are formed of a material that provides for the proper positive bearing and guiding action and yet wears away at a rate equal to the rate of reduction of the active diameter of the cutting parts 19 without scoring or cutting into the wall of the well bore. In practice, the parts 13 may be formed of a metal having a relatively

low resistance to abrasion, for example, they may be formed of bronze, brass, aluminum, etc. The bearing and guiding parts 13 are in the nature of blocks or separate pieces of the relatively soft material and are attached to or mounted on the body 10 by the means 14.

The means 14 for removably mounting the guide parts 13 on the body 10 is such that the parts 13 are dependably held in their operative positions during the drilling and allows the parts 13 to be easily and quickly removed from the body for replacement etc. The means 14 includes a boss or enlargement 29 on the exterior of the body 10 for carrying each of the guide parts 13. The enlargements 29 are arranged in a circumferential series on the lower or reduced body portion 16. In the particular form of the invention being described, there are three equally spaced enlargements 29. The enlargements 29 are preferably spaced a substantial distance above the pilot cutter 11. A recess or socket 30 is provided in each enlargement 29 to receive or carry a bearing part 13. The sockets 30 have comparatively large open outer sides and their forward ends, relative to the direction of rotation of the drill, are open. The rear ends of the sockets 30 are closed and their rear walls 31 form abutments for the bearing and guiding parts 13 as will be subsequently described. The upper and lower walls of the sockets 30 are under cut or provided with longitudinal grooves 32. The outer walls of the grooves 32 are preferably sloping as clearly illustrated in Figs. 1 and 4 of the drawings. The bearing and guiding parts 13 are shaped and proportioned to be slid into the open forward ends of the sockets 30. The parts 13 have flat inner ends or shoulders 33 adapted to bear against the abutment shoulders 31 at the rear ends of the sockets. Tongues 34 are provided on the upper and lower sides of the parts 13 to fit in or cooperate with the grooves 32.

In accordance with the invention, the guiding parts 13 project radially outward from the body enlargements 29 and their outer sides or ends are operable to engage the wall of the bore B. The opposite vertical sides 35 of the parts 13 may be flush with and form continuations of the sides of the body enlargements 29. The means 14 for removably attaching the parts 13 to the body 10 includes screws 36 for clamping or retaining the parts 13 in the sockets 30. There may be one screw 36 for retaining each part 13 in a socket. The screws 36 pass through openings 37 in the parts 13 and thread into openings 38 in the body 10. The heads of the screws 36 are preferably counter-sunk in the outer end portions of the openings 37. The outer end portions of the cutting parts 13 may be peened over into the outer ends of the openings 37 as at 39, to lock the screws against displacement. The retaining screws 36 may be formed of the same material as the guiding parts 13 or may be formed of a material having substantially the same qualities and characteristics as the material of the guiding and bearing parts. It will be obvious how the screws 36 are operable to securely and dependably hold the guiding parts 13 in their proper positions in the sockets 30. The screws 36 are not subjected to severe strains or pressures during operation of the drill, as pressures due to turning or rotation of the drill are directly transmitted from the shoulders 33 to the abutment shoulders 31. In a like manner, the upward forces on the guiding parts 13 due to the downward

feeding of the drill are directly transmitted to the upper walls of the sockets 30.

The guiding and bearing parts 13 in projecting radially outward from the enlargements 29 of the body are adapted to engage or cooperate with the wall of the bore B and in accordance with the invention, the parts 13 are proportioned to have their outer formation engaging faces 40 spaced the same distance from the axis of rotation of the drill as the outer edges 26 of the cutting blades 19. The outer sides or faces 40 of the bearing and guiding parts 13 are smooth and curved concentrically about the central vertical axis of the body 10 and are of considerable area so that the parts 13 do not cut or bite into the formation. The bearing and guiding parts 13, in being located at circumferentially spaced points around the exterior of the body, effectively center the lower portion 16 of the body in the bore B and thus stabilize the drill and guide to the drill to make a straight vertical bore.

It is believed that the operation of the embodiment of the invention illustrated in Figs. 1 to 4 inclusive of the drawings will be readily understood from the foregoing detailed description. As the bearing and guiding parts 13 are carried on the reduced lower portion 16 of the body 10, they do not engage the wall of the large major portion of the well bore as the drill is run into the well. When the lower portion 16 of the body enters the reduced lower bore portion B, or follows the pilot bit 11 into the bore B, the bearing and guiding parts 13 come into engagement with the wall of the reduced part B of the bore. The outer faces 40 of the bearing and guiding parts 13, in being spaced the same distance from the axis of rotation of the drill, engage or bear against the wall of the bore B, while the drill is rotated during the drilling operation. The pilot bit or cutter 11 cuts into the formation far in advance of the reaming cutter 12 and thus operates to guide the drill to make a straight bore.

The circumferentially spaced bearing and guiding parts 13 are spaced between the pilot cutter 11 and the reaming cutter 12 and effectively prevent the drill from taking an inclined course. Further, the circumferentially spaced bearing and guiding parts 13 stabilize the drill during operation, preventing it from wobbling, etc. The pilot cutter 11 is effective in rapidly cutting the small lower portion B of the bore as it acts on a comparatively small surface, and the reaming cutter 12, in making an annular cut at the upper end of the bore B is also rapid and efficient in operation. It is a feature of the invention that the bearing and guiding parts 13 are formed of a material having a relatively low resistance to abrasion so that they wear away as the blades 19 become reduced in width through wear. The parts 13 present comparatively large outer surfaces 40 for contacting with the formation and the blades 19 of the pilot cutter 11 operate to space the lower portion 16 of the body from the wall of the bore B so that the bearing parts are not worn away or reduced in thickness more rapidly than the blades 19. In this manner, the bearing and guiding parts 13 remain in active guiding engagement with the wall of the bore B during the life of the cutting blades 19. The parts 13 present large smooth surfaces 40 for engaging the formation and therefore do not cut into or score the wall of the bore B. It will be apparent how the three point contact of the spaced parts 13 with the wall of the bore B points between the cutters 11 and 12 positively guides

the drill to make a straight vertical bore and effectively stabilizes the drill to prevent it from wobbling. The circulation fluid discharging from the pilot cutter 11 flushes the blades 19 and the blades 21 and is free to flow upwardly around the lower portion 13 of the body between the parts 13 and then wash the blades 25 of the reaming cutter. The reaming cutter blades 25 project inwardly at the upper end of the reduced bore B, thus overlapping the blades 19 in their action on the formation so that their inner portions may assume a part of the cutting function when the blades 19 become materially reduced through wear. The screws 36 for retaining the parts 13 in position are formed of a material having a relatively low resistance to abrasion so that they may wear away together with the parts 13 without biting into the formation.

When the cutting parts of the drill and the bearing and guiding parts 13 become worn, the drill is removed from the well so that the cutting parts may be replaced and repaired, and so that the guiding parts 13 may be replaced. The parts 13 may be readily detachable from the body of the drill by merely unthreading the screws 36 from the openings 38 which allows the parts 13 to be slid out of the sockets 30. As described above, the bearing parts 13 are effectively supported against the thrusts and pressures to which they are subjected during operation of the drill. The inner ends of the parts 13 bear against the inner walls 32 of the sockets 30 and the rear sides of the parts bear against the abutment faces 31 so that the parts 13 are supported against inward pressures and the pressures imposed on them due to the rotation of the drill. Vertical forces on the parts 13 are transmitted directly to the upper and lower walls of the sockets 30. The bearing and guiding parts 13 are inexpensive of manufacture and therefore may be replaced at a minimum of expense.

The form of the invention illustrated in Figs. 5, 6 and 7 of the drawings is in the nature of a double barreled core drill and includes, generally, an outer barrel or body 41, a bit head 42 on the lower end of the body, an inner core receiving barrel 43, bearing and guiding parts 44, and means 45 for removably attaching the parts 44 to the body 41.

The body 41 of the core drill is an elongate tubular structure carrying the various other parts of the tool. The body 41 includes a main portion or barrel proper 46, adapted to be connected with the lower end of an operating string of drill pipe, or the like. A sub or connecting member 47 is threaded on the lower end of the barrel 46. The body 41 includes a bit head sub or member 48 for connecting the bit head 42 with the member 47. The members 47 and 48 are tubular and are preferably of the same external and internal diameters. A threaded pin 49 is provided on the lower end of the member 48 to facilitate connection with the bit head 42.

The bit head 42 is attached to the lower end of the body 41 and is operable to make an annular cut in the earth formation, and thus form a core C to be received by the inner barrel 43. The bit head 42 includes a tubular body or shoe 50 and cutting parts 51. A threaded socket 52 is provided in the upper end of the shoe 50 for receiving or cooperating with the pin 49. An annular internal channel or recess 53 is provided in the shoe 50 at the lower end of the socket 52. The cutting parts 51 may be in the nature of blades projecting downwardly and outwardly from the

lower end of the shoe 50. Spaced ports 54 are provided in the bit head for discharging fluid downwardly on the forward faces of the blades 51.

5 The inner barrel 43 which extends longitudinally through the tubular body 41 is provided to receive and hold the core C. The inner barrel 43 extends through the body 41 with substantial clearance providing an annular passage for the downward flow of the circulation fluid or rotary mud. In the particular drill structure illustrated, the inner barrel 43 has its lower end rotatably supported in the bit head 42 so that it may be held against rotation with respect to the core C during drilling when the frictional engagement with the core is sufficient to hold it against turning. An enlargement or collar 55 is provided on the lower end of the inner barrel 43 and is rotatably supported in the annular recess 53 of the shoe 50. Ports 56 are provided in the collar 55 to connect the annular space between the inner barrel 43 and the body 41 with an annular space on the upper ends of the ports 54.

20 The core drill includes a core catcher for retaining or supporting the core C in the drill when the drill is removed from the well bore. In accordance with the broader aspects of the invention, any suitable or practical form of core catcher may be provided in the drill. The particular core catcher illustrated in the drawings includes an annular body 57 rotatably supported in the annular recess 53 of the shoe 50 and extending into the lower end of the collar 55. Pivoted dogs 58 are provided on the core catcher body 57 for biting into the core C when the drill is raised to break the core free from the formation and to thereafter support the core C when the drill is pulled from the well. The dogs 58 are pivoted upwardly and outwardly to retracted positions as the core enters the drill.

25 The bearing and guiding parts 44 are provided on the exterior of the body 41 to engage the wall of the well bore X to stabilize the drill and to guide the drill to make a straight vertical hole. In accordance with the invention, the bearing and guiding parts 44 are mounted on the exterior of the body a considerable distance above the cutting parts or blades 51. It is a feature of the invention that the boring and guiding parts 44 wear away or become reduced in effective diameter as the cutting blades 51 become reduced in size through wear so that they effectively guide the drill throughout the life of the cutting parts without causing the drill to bind or stick in the bore. The parts 44 are formed of a material having a relatively low resistance to abrasion to readily wear away as the cutting parts 51 become reduced in width through wear, so that they do not score or cut into the wall of the bore X. In practice, the bearing and guiding parts 44 may be formed of bronze, brass, or a like relatively soft metal. The bearing and guiding parts 44 are simple, inexpensive blocks or members and are alike in size and configuration.

30 65 The means 45 for removably attaching the bearing and guiding parts 44 to the body 41 operate to dependably hold the parts 44 in their proper positions during operation of the drill, and are such that the parts 44 may be easily removed for replacement. A plurality of circumferentially spaced body bosses or enlargements 59 are included in the means 45 for carrying the parts 44. The enlargements 59 are provided on the exterior of the body 41 and in the form of the invention being described, are provided on the coupling or

35 50 connecting member 48. In the particular construction illustrated, there are three equally spaced projections or enlargements 59 on the member 48. A socket 60 is provided in each enlargement 59 to receive or carry a bearing and guiding part 44. The sockets 60 extend upwardly from the lower ends of the enlargements 59 having open lower ends and open outer sides. The upper ends or walls 61 of the sockets 60 form abutments for the parts 44. The sockets 60 are substantially rectangular in cross sectional configuration and their vertical side walls are provided with grooves 62. The outer walls of the grooves 62 are preferably outwardly convergent as clearly illustrated in Fig. 6 of the drawings. 15 The bearing and guiding parts 44 are shaped and proportioned to fit into the sockets 60. In assembling the parts 44 on the drill, they are slid or passed upwardly into the lower ends of the sockets 60. Tongues 63 are provided on the opposite vertical sides of the parts 44 to fit the grooves 62. The upper ends of the bearing and guiding parts 44 are flat and seat upwardly against the abutment shoulders 61. The means 45 includes screws 64 threaded through horizontal or transverse 20 openings in the parts 44 and extending into sockets or openings 65 in the inner walls of the sockets 60. The inner ends of the screws 64 react against the ends of the openings 65, clamping the parts 44 outwardly so that their tongues 63 are tightly 25 held or wedged in the grooves 62. The screws 64 may be socket-headed and their heads are preferably counter-sunk in the outer end portions of the parts 44. The screws 64 are preferably formed of a relatively soft metal or a metal having the same 30 characteristics as the parts 44.

35 40 The outer faces or surfaces of the enlargements 59 are preferably curved concentrically about the central vertical axis of the body 41. In accordance with the invention, the guiding and bearing parts 44 project radially outward from the enlargements 59 and their outer faces 67 are operable to engage the wall of the well bore X to guide and stabilize the drill. If desired, the outer projecting portions of the bearing and guiding parts 44 may be formed to overlie the outer faces of the enlargements 59. This provides the parts 44 with large bearing or formation engaging surfaces 67. The surfaces 67 are preferably concentrically curved about the central vertical axis of the drill. 50 In accordance with the invention, the active or formation engaging surfaces 67 of the bearing and guiding parts 44 are spaced the same distances from the axis of rotation of the drill as the outer or reaming edges of the blades 51.

55 60 In the operation of the form of the invention illustrated in Figs. 5, 6 and 7 of the drawings, the cutting parts 51 of the bit head operate to make an annular cut in the earth formation providing the core C which is received in the inner barrel 43. The circulation fluid is passed downwardly between the inner barrel and the body to discharge from the ports 54 of the bit head to flush the cutting parts 51 and to provide the necessary turbulence in the lower end of the bore. The 65 circulation fluid is free to flow upwardly around the body 41 between the bearing and guiding parts 44. As the outer faces 67 of the parts 44 are spaced the same distance from the vertical center of the drill as the outer edges of the cutting parts 51, they engage or contact the walls of the bore to stabilize the drill and to guide the drill to make a straight vertical bore. As the parts 44 are formed of material having a relatively low resistance to abrasion, they do not cut into or 70 75

score the walls of the well bore X and wear away as the cutting parts 51 become reduced in width through wear without causing the drill to stick or bind in the well. The parts 44 are spaced a considerable distance above the cutting parts 51 and are circumferentially spaced to insure the effective centralizing of the drill in the bore and to stabilize the drill. As the cutting parts 51 become reduced in effective size through wear, 10 the bearing and guiding parts 44 likewise become reduced in size so that they at all times are capable of having bearing and guiding engagement with the wall of the bore X without cutting into the formation and without causing the drill to bind. The abutment shoulders 61 effectively support the bearing and guiding parts 44 against upward thrusts, while the rear side walls of the sockets 61 support the parts against the strains imposed upon them due to the rotation of the 20 drill. The screws 64 clamp the parts 44 outwardly so that their tongues 63 are securely wedged in the grooves 62 and the screws may take the inward thrusts or pressures imposed on the parts 44. When the cutting parts 51 and 25 the bearing parts 44 become worn to an appreciable extent, or when a core of sufficient length has been received, the drill is raised, causing the dogs 58 to bite into the core to break it from the formation and the drill may then be withdrawn 30 from the well. The parts 44 may be easily and quickly detached from the body 41 by unthreading the screws 64 which allows the parts to be slid downwardly out of the sockets 60.

Figs. 8 to 10 inclusive of the drawings illustrate another form of the invention embodied in a single barreled core drill or core receiving drilling tool. This form and application of the invention includes generally, a tubular body 10, a cutter head or bit head 71 on the lower end of 35 the body, core catching means 72, and replaceable guiding and bearing parts 73 on the exterior of the body 10 for guiding and stabilizing the drill.

The body 10 is adapted to be attached to the 40 lower end of the drilling string and is an elongate tubular structure including an upper portion or barrel 74. A sub or tubular connecting member 75 is threaded on the lower end of the barrel 74 and is provided at its lower end with a 45 threaded pin 76. A tubular member 77 is threaded on the pin 76 and forms the body of the core catching means 72, and carries the bit head 71. As illustrated in the drawings the member 77 is comparatively long.

The cutter head or bit head 71 is attached to the 50 lower end of the member 77 and is operable to make an annular cut or bore Y, and provide the core Z. The bit head 71 includes a tubular body or shoe 78 threaded on to the lower end of the member 77. Cutting parts 79 are provided 55 on the body or shoe 78 of the bit head. In the particular drill illustrated in the drawings, the cutting parts 79 are in the nature of blades, it being understood that any suitable form of cutting parts may be provided on the bit head. The cutting parts 79 project downwardly and outwardly from the lower end of the shoe 78 and have comparatively long outer or reaming edges 80 for engaging the side wall of the bore Y. In 60 the single barreled core receiving drill illustrated in Figs. 8 and 9, the circulation fluid is passed downwardly through the body 10 around the core Z to discharge from the bit head 71 at the point where the core enters the drill. The circulation 65 fluid then flows upwardly around the drill body 70

75 to ultimately flow from the upper end of the well bore.

The core catching or retaining means 72 includes a tubular body member 77 attached to the lower end of the member 74 and carrying the bit head 71. Elongate blocks 81 are set in slots 82 in the wall of the member 77. Core gripping and supporting dogs 83 are pivotally mounted in recesses 84 in the inner sides of the blocks 81 and are adapted to project into the interior of the 10 body to engage the core Z. The dogs 83 are adapted to pivot upwardly and outwardly to retracted positions as the core Z enters the drill. Upon an upward movement of the drill the pointed inner ends of the dogs 83 bite into the 15 core Z and cause the core to be broken away from the formation. The dogs 83 thereafter support the core Z in the drill as the drill is removed from the well bore.

The bearing and guiding parts 73 are removably mounted on the exterior of the body 10 a substantial distance above the bit head 71 to engage the wall of the well bore Y and guide and stabilize the drill. In accordance with the form of the invention being described, the guiding and bearing parts 73 are provided on the coupling or connecting member 75. The parts 73 are formed of a relatively soft material such as bronze, brass, or a like metal having a relatively low resistance to abrasion. In accordance with 20 the invention, the bearing and guiding parts 73 are detachably mounted on the member 75 so that they may be readily replaced. A plurality of circumferentially spaced enlargements 86 are provided on the exterior of the member 75 to 25 carry the parts 73. In the particular case illustrated in the drawings, there are three equally spaced enlargements 86. Slots or sockets 87 are provided in the enlargements 86 to carry or hold 30 the guiding parts 73. The sockets 87 extend vertically through the enlargements 86 from their lower ends to their upper ends and the outer sides of the sockets are open to pass the projecting 35 end portions of the guiding parts 73. Vertical key-ways or grooves 88 are provided in the side 40 walls of the sockets 87. The walls of the grooves 88 taper or converge upwardly as clearly illustrated in Fig. 10 of the drawings.

The bearing and guiding parts 73 are shaped and proportioned to be passed upwardly into the 45 lower ends of the sockets 87. Tongues 89 are provided on the opposite vertical sides of the parts 73 to cooperate with the grooves 88. The faces of the tongues 89 are upwardly convergent so as to wedge against the walls of the grooves 88. In 50 accordance with the invention, the bearing and cutting parts 73 project radially outward from the enlargements 86 to engage the wall of the bore Y and project beyond the upper and lower 55 ends of the slots or sockets 87. The projecting upper end portions 91 of the parts 73 are preferably peened over to prevent the parts 73 from becoming displaced from the sockets 87. If found desirable or necessary, the projecting 60 lower end portions 92 of the parts 73 may also be peened over or may be initially formed to bear upwardly against the lower ends of the enlargements. The outer formation engaging faces 93 65 of the parts 73 are comparatively large in area 70 and are concentrically curved about the central vertical axis of the drill. The outer surfaces 93 of the bearing and guiding parts 73 are spaced of the same distance from the axis of rotation of 75 the drill as the outer edges 80 of the cutting parts 75

49 so that they may at all times engage the wall of the bore Y.

In the operation of the form of the invention disclosed in Figs. 8, 9 and 10 of the drawings, the drill is rotated in the well bore so that the cutting parts 49 make the annular cut or bore Y and form the core Z. The core Z is received by or extends upwardly into the body of the drill, and the circulation fluid flows downwardly through the body around the drill to discharge at the bit head 71. During the drilling operation, the outer faces 83 of the bearing and guiding parts 73 slidably engage the walls of the well bore Y to effectively guide the drill and to stabilize the drill. In being spaced substantial distances apart, the guiding parts 83 and the enlargements 86 do not interfere with the free upward flow of circulation fluid around the body 10. The bearing and guiding parts 73, in being formed of a relatively soft material having a low resistance to abrasion and wear away as the cutting parts 49 become reduced in effective size through wear and do not score or cut into the wall of the bore Y. The formation engaging faces 93 of the parts 73 continue to be spaced the same distances from the vertical center of the drill as the outer edges 86 of the cutting parts throughout the life of the cutting parts so that the cutting parts are at all times active and effective in stabilizing and guiding the drill. When the drill is pulled or removed from the well bore, the dogs 83 bite into the core Z to break the core free from the formation and to thereafter support the core in the drill as the drill is removed from the well. The worn guiding parts 73 may be easily detached from the drill and replaced. To remove the worn parts 73, the peened over upper portions 81 are cut off or removed so that the parts 73 may be readily driven downwardly out of the sockets 87. During operation of the drill the bearing and guiding parts 73 closely fit in the tapering sockets 87 so that they are dependably held and supported against the pressures and forces to which they are subjected.

Having described only typical forms and applications of the invention, I do not wish to be limited or restricted to the specific forms and applications herein described, but wish to reserve to myself any variations or modifications that may appear to those skilled in the art or fall within the scope of the following claims:

Having described my invention, I claim:

1. In a well drill, a body adapted to be connected with a bit head, a projecting enlargement on the exterior of the body to be spaced above the head, the enlargement having a socket having an open outer side, a closed end wall and a normally open end opposite said wall and grooves in its side walls, a guide part adapted to be passed into the open end of the socket to bear on said end wall and project from its open outer side to engage the wall of the well bore, and tongues on the guide part cooperating with the grooves to hold the guide part in the socket.
2. In a well drill, a body adapted to be connected with the bit head of the drill, there being circumferentially spaced sockets in the exterior of the body to be spaced above the head, each socket having an open outer side and an open end and grooves in its walls, guide blocks adapted to be passed into the open ends of the sockets to project from the open outer sides to engage the wall of the well bore, tongues on the guide

blocks cooperating with the grooves, and screws detachably retaining the guide blocks in the sockets.

3. In a well drill including, a body adapted to be connected to the bit head of the drill, external enlargements on the body, there being a socket in each enlargement having an open outer side and an open forward end relative to the direction of rotation of the drill, guide blocks adapted to be passed into the forward ends of the sockets to bear on the rear ends of the sockets and project outwardly through the outer sides of the sockets, and screws passing through openings in the guide blocks and threaded into the body to removably attach the blocks to the body.

4. In a well drill, a body adapted to be attached to the bit head of the drill, external enlargements on the body, there being a socket in each enlargement having an open outer side and an open lower end, there being grooves in the opposite vertical side walls of the sockets, guide parts adapted to be passed into the lower ends of the sockets to project from the outer sides of the sockets, tongues on the guide parts cooperating with the grooves, there being openings in the inner walls of the sockets, and screws threaded through the guide parts and reacting against the walls of said openings to detachably clamp the tongues against the outer walls of the grooves to lock the guide parts in position.

5. In a well drill, a body to be attached to the bit head of the drill, there being circumferentially spaced sockets in the exterior of the body, each socket having an open outer side and an open lower end, the vertical side walls of the sockets being upwardly convergent, and guide parts adapted to be passed into the lower ends of the sockets to project outwardly through the outer ends of the sockets, the opposite sides of the guide parts being upwardly convergent to wedge against the convergent walls of the recess, the guide parts including upper portions projecting from the upper ends of the sockets and peened over to prevent displacement of the parts.

6. Guide means for use with a well drill including a tubular member having a thread at one end for connecting with a part of the drill and a thread at the other end for connecting with another part of the drill, spaced projections on the member each having a socket and a passageway leading from an external surface to its socket, there being grooves in opposite side walls of the sockets, guide parts adapted to be passed through the passageways into the sockets to project therefrom to engage the well bore, tongues on guide parts for cooperating with the grooves, and means for detachably locking the guide parts in the sockets.

7. In guide means for a well drill, a body adapted to be connected with cutting means for making a bore, a projection on the body, the projection having a socket with an open outer side and grooves in its walls, a guide block adapted to project through said outer side of the socket to engage the wall of the bore, tongues on the guide block cooperating with the grooves, the projection having a passage leading from an external surface of the projection to the socket to pass the guide block into the socket, and a screw locking the guide block in the socket.

JESSE C. WRIGHT.
